UNITED STATES PATENT OFFICE.

G. SLOCUM AND M. T. SAYLES, OF LANSINGBURG, NEW YORK.

MACHINERY FOR CRIMPING METAL BARS.

Specification of Letters Patent No. 9,392, dated November 9, 1852.

To all whom it may concern:

Be it known that we, GILES SLOCUM and M. T. SAYLES, of Lansingburg, in the county of Rensselaer and State of New York, have 5 invented a new and Improved Machine for Crimping Bars of Iron for Ornamental Fences, &c.; and we do hereby declare that the following is a full, clear, and exact description of the construction and operation 10 of the same, reference being had to the annexed drawings, making a part of this specification, in which—

Figure 1, is a longitudinal vertical section of the machine taken at the line X, X, Fig. 15 3. Fig. 2, is a plan or top view of ditto. Fig. 3, is an end view of ditto in elevation.

Similar letters of reference indicate corresponding parts in each of the several figures.

20 This invention relates to an improved machine for crimping or bending bars of iron for ornamental fencing, stair stringers, and other purposes where bars thus bent or crimped may be applied.

25 The invention consists in a peculiar manner of operating a pair of dies, one or both of which may be flexible, said dies passing between pressure rollers which force the dies together and crimp or bend the iron as will 30 be fully described hereafter.

To enable others skilled in the art to make and use our invention we will proceed to describe its construction and operation.

35 A, represents a frame constructed in any suitable manner.

B, B', are stationary rollers placed transversely in the frame A, as seen in Fig. 1.

C, is a movable bed on the upper part of 40 which is secured the female die D. The male die E, is secured by a pivot (a) to one end of the female die as seen in Fig. 1. The female die D, is solid, or is not flexible, while the male die E, is flexible, it having

45 a series of joints (b). The female die is formed of a series of triangular shaped recesses, and the male die is formed of a series of triangular shaped projections connected by the pivots (b) which projections 50 fit into the recesses when the dies are pressed together.

The movable bed C, to which the dies are attached works or moves on the stationary

rollers B, B', a cord F, being attached to the roller B', and to the underside of the bed C. 55

G, G, are rollers directly over the stationary rollers B, B'. The axes of the rollers G, G, have their bearings in slide rods H, which work in vertical uprights I, attached to the frame A. Two levers J, J, bear upon 60 the upper ends of these slide rods H, the levers having arms (c) which rest over the upper ends of the slide rods, see Fig. 2. At the end of each lever J, there is attached a weight K, see Fig. 1, and dotted lines in 65 Fig. 2, these weights cause the arms (c) of the levers J, J, to bear upon the upper ends of the slide rods H, and consequently keep the rollers G, G, depressed and cause them to bear or press upon the male die E, as will 70 be presently shown.

L, Fig. 1 is a bar of iron placed over the female die D, the bar L, is placed in this position when it is to be crimped or bent.

The operation of the machine will be readily seen. The bar L is placed over the female die D, as just shown and power is applied to the roller B', by the turning of a crank or pulley, the roller B', as it revolves winds upon it the cord F, and the movable 80 bed C, with the male and female dies E, D, is forced between the rollers B', B, and G, G, the rollers G, G, in consequence of the weights K, K, acting upon the slide rods H, bearing or pressing the male die upon the 85 bar L, and forcing said bar into the triangular recesses of the female die D. The front roller acts of course upon the first projection of the male die and after that is forced into the first recess of the female die the second 90 roller retains the bar L, and prevents it from being withdrawn as the first roller acts upon the succeeding projection of the male die E. Thus the movable bed C, is moved along until the whole length of the dies have 95 passed between the rollers, and the bar bent or crimped.

We do not claim the flexible die E, nor the combination of the permanent die D, and flexible die E, as they have been previously 100 used, but—

What we do claim as our invention, and desire to secure by Letters Patent, is—

The peculiar manner of operating said dies as herein shown and described, viz. By 105 means of the pressure rollers G, G, and B,

B'. The lower rollers B, B', being fixed permanently in the frame, and the upper rollers G, G, arranged so as to yield to the die when necessary. The movable bed C, being attached by a cord or chain to the roller B', by turning which the bed C, is drawn between the upper rollers G, G, and the lower rollers B, B'. The upper rollers

forcing or compressing the flexible die E, upon the permanent die D, and bending or crimping the bar as set forth.

GILES SLOCUM.
M. T. SAYLES.
